UNITED STATES PATENT OFFICE.

AXEL PERSON, OF ATTLEBORO, MASSACHUSETTS, ASSIGNOR TO HARVEY CLAPP & CO., OF ATTLEBORO, MASSACHUSETTS, A PARTNERSHIP.

BRACELET CONSTRUCTION.

Application filed December 30, 1926, Serial No. 157,909. Renewed November 30, 1927.

This invention relates to bracelet construction and more particularly to extensible bracelets. One of the objects thereof is to provide an extensible bracelet of practical construction and capable of meeting the requirements of practical use in a highly satisfactory manner. Another object is to provide a construction of the above nature which is strong and rugged. Another object is to provide a construction of the above nature wherein units of the bracelet may be inserted or removed with convenience to vary the length of the bracelet. Another object is to provide a construction of the above nature which, when assembled, is not likely to become disarranged in use. Another object is to provide a construction of the above nature which is neat and attractive in appearance. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which is shown one of the various possible embodiments of this invention,

Figure 1 is a top plan view of the bracelet shown somewhat diagrammatically and with the middle portion thereof broken away;

Figure 2 is a bottom view of a portion of the bracelet shown partly in elevation and partly in section;

Figure 3 is a view taken along the line 3—3 of Figure 2;

Figure 4 is a bottom view of a portion of the bracelet showing the bracelet units in extended position and with parts thereof broken away;

Figure 5 is a side elevation of part of Figure 4;

Figure 6 is a section taken along the line 6—6 of Figure 3, and

Figure 7 is a section taken along the line 7—7 of Figure 3.

Similar reference characters refer to similar parts throughout the several views of the drawing.

Referring now to the drawing in detail, there is shown in Figure 1 a bracelet made up of a series of bracelet units indicated

generally by the numeral 10, these units being hinged together as will be described in detail hereinafter. This bracelet in Figure 1 is shown provided with a pair of end clasps 11 by means of which the bracelet ends may be attached to a wrist watch or the like. It is to be understood, however, that the construction described hereinafter is not limited, in its use, to a wrist watch bracelet as the bracelet construction may be employed to advantage in other relations.

The separate units 10 of this bracelet are preferably all substantially identical in construction and each comprises an outer link and an inner link which is slidably mounted therein and urged thereinto by a spring. The outer link has a top wall 12 and depending side walls 13 and 14. These side walls 13 and 14 are bent or extended inwardly at the bottom, as shown at 13^a and 14^a, and thence are extended upwardly toward the top wall 12, forming vertical inner walls 13^b and 14^b which extend parallel to and are spaced a short distance from the outer side walls 13 and 14 respectively. As is best seen in Figure 6, the walls 13^b and 14^b are spaced at their upper edges from the under surface of the top wall 12. Also, these walls 13^b and 14^b with the respective walls 13 and 14 form what might be termed a pair of longitudinally extending channels, one at either side of the outer link.

The inner link which is slidably mounted in the outer link comprises a top wall 15, a bottom wall 16 and end walls 17 and 18. This slideable inner link has also depending side walls 19 and 20. As may be seen in Figure 6, the top wall 15 of the inner link is slidably received between the upper edges of the parts 13^b and 14^b and the bottom surface of the upper wall 12 of the outer link. The side walls 19 and 20 of the inner link are slidably received in and guided by the longitudinal channels formed between the walls 13 and 13^b and the walls 14 and 14^b respectively. The bottom wall 16 of the inner link is received between the parts 13^a and 14^a, and its surface is preferably substantially flush with the surfaces of these two parts.

Within the inner slideable link is positioned a spring 21 which urges the parts to take the contracted position shown in Figures 2 and 3. In Figure 4 the bracelet units shown are in extended position, the inner

link being slid out of the outer link and the spring 21 being compressed. The spring 21, at one end, bears against the end wall 16 of the inner link. At its other end the spring 5 bears against a spring abutment which preferably takes the form of a pair of lugs 22 and 23. These lugs are preferably formed integrally with the respective portions 13^b and 14^b of the outer link, extending inward- 10 ly therefrom toward each other. The end of these lugs are preferably bent at right angles to provide portions 22^a and 23^a which enter the end of the spiral spring. By this construction the spring is dependably held 15 in its proper position.

At the left-hand end of the outer link, as viewed in the drawing, the side walls 13 and 14 project outwardly providing rounded end portions 13^c and 14^c. Between these two 20 parts 13^c and 14^c is a connecting member preferably taking the form of a rivet or pintle 25. At the other end of the outer link the ends of the side walls 13 and 14 are concave and rounded to mate with the rounded 25 end portions 13^c and 14^c of the next adjoining bracelet unit.

The bottom wall 16 of the slideable inner link is split, as shown at 26, adjacent the end thereof remote from the pintle 25. The 30 end 18 of the inner link thus provides a hook which is adapted to detachably engage the pintle 25 of the adjoining bracelet unit to connect the bracelet units together.

The split 26 preferably extends across the 35 bottom wall 16 diagonally, one end thereof being further from the end wall 18 than is the other end thereof. This gives the lip of the hook a taper or an incline which insures a dependable locking of the hook over the 40 pintle of the next bracelet unit. In joining the units or in separating them, the inner link is first pulled out to its extended position, compressing the spring 21, and then the bottom wall 16 adjacent to the hook is depressed, as shown in Figure 5. Thereupon, 45 the link are swung to the relative positions which are indicated in Figure 5, and then the pintle 25 may be moved through the split 26 by twisting the position of the two links 50 with respect to one another, as indicated by the position of the pintle 25 at the right-hand side of Figure 4. The links can not be thus twisted without first swinging them to the relative positions shown in Figure 5 and 55 without holding the inner link extended against the action of the spring 21, and thus the possibility of the links being detached unintentionally is extremely remote. However, when it is desired to remove or insert 60 a unit of the bracelet in order to change its length, this can be accomplished very conveniently without requiring the use of tools.

It will be seen that this bracelet is exceptionally strong and rugged and yet of 65 simple construction. The double side walls

of the outer links serve to strengthen the construction and, the side walls of the inner links being supported and guided between these double walls, the stability of the entire construction is greatly enhanced. Moreover, 70 the bracelet presents an attractive appearance from the top and from the sides whether it be in contracted or extended position.

As many possible embodiments may be 75 made of the above invention and as many changes might be made in the embodiment above set forth, it is to be understood that all matter hereinbefore set forth or shown in the accompanying drawing, is to be interpreted as illustrative and not in a limiting 80 sense.

I claim as my invention:

1. A bracelet comprising a plurality of 85 bracelet units connected together, each of said units including, in combination, an outer link having a top wall and side walls depending therefrom, said side walls being bent inwardly at the bottom and thence extending upwardly toward the under side of 90 said top wall and forming beneath said top wall a pair of longitudinal channels one at either side of said link, and an inner link slideable longitudinally within said outer link and having a top wall and depending side 95 walls, said side walls resting in said channels.

2. A bracelet comprising a plurality of 100 bracelet units connected together, each of said units including, in combination, an outer link having a top wall and side walls, an inner link slideable within said outer link and having top, bottom and end walls, a pair 105 of lugs at one end of said outer link formed integrally with said side walls thereof and projecting inwardly toward each other, and a spring within said inner link acting between an end wall thereof and said lugs, the inner ends of said lugs being bent to extend longitudinally of said link and entering the 110 end of said spring.

3. A bracelet comprising a plurality of 115 bracelet units connected together, each of said units including, in combination, an outer link having a top wall and side walls 120 depending therefrom, said side walls being bent inwardly at the bottom and thence extending upwardly toward the under side of said top wall and forming beneath said top wall a pair of longitudinal channels one at 125 either side of said link, and an inner link slideable within said outer link having top, bottom and end walls and side walls depending from said top wall, said side walls resting in said channels and said inner link having means adjacent one end for connection with the next adjoining bracelet unit.

4. A bracelet comprising a plurality of 130 bracelet units connected together, each of said units including, in combination, an

- outer link having a top wall and side walls depending therefrom, said side walls being bent inwardly at the bottom and thence extending upwardly toward the under side of 5 said top wall and forming beneath said top wall a pair of longitudinal channels one at either side of said link, an inner link slideable within said outer link having top, bottom and end walls and side walls depending 10 from said top wall, said side walls resting in said channels, a spring abutment between said upwardly extending portions of the side walls of said outer link, and a spring within said inner link acting between an end 15 wall thereof and said spring abutment.
5. A bracelet comprising a plurality of bracelet units connected together, each of said units including, in combination, an outer link having a top wall and side walls depending therefrom, said side walls being bent inwardly at the bottom and thence extending upwardly toward the under side of 20 said top wall and forming beneath said top wall a pair of longitudinal channels one at either side of said link, an inner link slideable within said outer link having top, bottom and end walls and side walls depending from said top wall, said side walls resting in said channels, a pair of inwardly 25 projecting lugs adjacent one end of said outer link formed integrally with said upwardly extending portions of the side walls thereof, and a spring within said inner link acting between an end wall thereof and said lugs.
35. 6. A bracelet comprising a plurality of bracelet units connected together, each of said units including, in combination, an outer link having a top wall and side walls depending therefrom, said side walls being bent inwardly at the bottom and thence extending upwardly toward the under side of 40 said top wall and forming beneath said top wall a pair of longitudinal channels one at either side of said link, an inner link slideable within said outer link having top, bottom and end walls and side walls depending from said top wall, said side walls resting in said channels, a spring abutment between said side walls of said outer link 45 adjacent one end thereof, a spring within said inner link acting between an end wall thereof and said spring abutment, said bottom wall of said inner link being split to form a hook for connection with an adjoining bracelet unit, and means between said side walls of said outer link at the end thereof remote from said spring abutment for operating with the hook of an adjoining unit.
55. 7. A bracelet comprising a plurality of bracelet units connected together, each of said units including, in combination, an outer link having a top wall and a pair of upright longitudinally extending walls at each 60 side thereof, means connecting said upright

walls together along one of the longitudinal edges thereof, and an inner link slideable within said outer link and having a pair of side walls resting respectively between and guided by said two pairs of upright walls 70 of said outer link.

8. A bracelet comprising a plurality of bracelet units connected together, each of said units including, in combination, an outer link having a top wall and at each side 75 thereof depending side walls and between said side walls a pair of inner walls positioned respectively adjacent to said two side walls and substantially parallel thereto, the top edges of said inner walls being spaced 80 from the under side of said top wall, and an inner sliding link having a top wall positioned beneath the top wall of said outer link and depending side walls resting respectively between one of said side walls and one of 85 said inner walls of said outer link, each of said inner walls being connected along its bottom edge to the adjacent side wall of the outer link.

9. A bracelet comprising a plurality of 90 bracelet units connected together, each of said units including, in combination, an outer link having a top wall and at each side thereof depending outer side walls and between said side walls a pair of inner walls positioned respectively adjacent to said two side walls and substantially parallel thereto, each of said inner walls being connected to its adjacent outer wall along its bottom edge, the top 95 edges of said inner walls being spaced from the under side of said top wall, an inner link having a top wall positioned beneath the top wall of said outer link and depending side walls resting respectively between one of said side walls and one of said inner walls of said outer link, and a spring positioned between said two inner walls and acting to hold said inner link against sliding outwardly from within said outer link.

10. A bracelet comprising a plurality of 100 bracelet units connected together, each of said units including, in combination, an outer link having a top wall and side walls depending therefrom, said side walls being bent inwardly at the bottom and thence extending upwardly toward the under side of said top wall and forming beneath said top wall a pair of longitudinal channels one at either side of said link, an inner link slideable longitudinally within said outer link and having top, bottom and end walls, means depending from the sides of the top wall of 105 said inner link adapted to slide in said channels, and a spring positioned between said upwardly extending portions of the side walls of said outer link and covered at the bottom of the bracelet unit by said bottom wall of the inner link, said spring acting to hold said inner link against sliding outwardly from said outer link.

11. A bracelet comprising a plurality of bracelet units connected together, each of said units including, in combination, an outer link having a top wall and at each side 5 thereof depending side walls, said side walls being extended inwardly at their bottom edges and thence being bent upwardly forming a pair of inner walls positioned respectively adjacent to said two side walls 10 and substantially parallel thereto, the top edges of said inner walls being spaced from the under side of said top wall, a band-shaped inner link slidable longitudinally in said outer link and having formed integrally 15 therewith a pair of depending sides resting respectively between one of said side walls and the adjacent inner wall of said outer link, and a spring positioned within said band-shaped link and acting to hold the 20 same against sliding outwardly from said outer link.
12. A bracelet unit adapted to be connected to similar units to form a bracelet chain and comprising, in combination, an 25 outer link having side walls, a connecting member between said side walls adjacent one end thereof, an inner link slidable within said outer link and having top, bottom and end walls, and a spring within said inner link bearing 30 against one end thereof and tending to hold said inner link within said outer link, said bottom wall of said inner link being split diagonally adjacent the end thereof opposite to that against which the 35 spring bears to form a hook, the lip of which is longer on one side than on the other, said hook being adapted to detachably engage the connecting member between the side walls of the outer link of another bracelet unit. 40
13. A bracelet unit adapted to be connected to similar units to form a bracelet chain and comprising, in combination, an outer link having side walls, a connecting member between said side walls adjacent one end thereof, an inner link slidable within said outer link and comprising a sheet metal band, the ends of which are cut diagonally and face each other at the bottom wall of the link and adjacent one end thereof, and a spring within said inner link bearing 45 against the end wall thereof opposite said first end and urging said inner link into said outer link, one of said diagonally cut ends forming a hook the lip of which is longer on one side than on the other, said hook being adapted to detachably engage the connecting member between the side walls of the outer link of another bracelet unit. 50
14. A bracelet unit adapted to be connected to similar units to form a bracelet chain and comprising, in combination, an outer link having a top wall and side walls, a pin extending between said side walls adjacent one end of said link, an inner link slidable within said outer link and comprising a sheet metal band the ends of which face each other adjacent one end of the bottom wall of the link, said inner link having side walls depending from the top wall thereof, 65 a spring within said inner link bearing against the end thereof opposite to said first end and urging said inner link into said outer link, said two ends of said inner link member being substantially parallel and extending diagonally in the bottom wall of the link, said end portion of the link thus having a hook the lip of which is longer on one side than on the other, said hook being adapted to detachably engage the connecting pin between the side walls of the outer link of another bracelet unit. 70
- In testimony whereof, I have signed my name to this specification this twenty-first day of December, A. D. 1926.
